UNITED STATES PATENT OFFICE.

CLARK F. FISK, OF CAMDEN, NEW JERSEY, ASSIGNOR, BY DIRECT AND MESNE ASSIGNMENTS, OF ONE-SIXTH TO SAMUEL H. BELL, OF READING, PENNSYLVANIA, ONE-THIRD TO J. H. MCNEAL, AND ONE-HALF TO B-N-B RUBBER COMPANY, A CORPORATION OF DELAWARE.

NURSING BOTTLE.

Application filed November 3, 1924. Serial No. 747,625.

This invention relates generally to nursing bottles and particularly to a casing to surround an ordinary nursing bottle to serve, first, as a protector for the same, second, as a means for securely holding the nipple upon the neck of the bottle, third, as a container for a heating or cooling fluid, and fourth, as a toy and teething appliance.

According to the invention the casing is 10 molded of rubber and when used around an ordinary glass nursing bottle, forms a cushion around the bottle to prevent the latter from being broken when dropped or struck against a hard object. The casing also 15 serves to prevent the glass of the bottle from scattering in case it should be broken or crushed.

The casing is fluid-tight and is provided with a restricted opening through which the 20 nipple and the neck of the nursing bottle extends. The material of the casing at the edges of this opening is intended to fit tightly against the portion of the nipple surrounding the neck of the bottle and not only 25 maintaining the nipple firmly upon the neck of the bottle but to also provide a fluid-tight joint between the opening and the neck of the bottle, so that heating or cooling fluid placed in the casing around the bottle will 30 not leak out.

Preferably the casing is molded in the form of a doll, so that it presents the appearance of and may be used as a toy. In 35 molding the casing a rib or projection may be formed upon the outside to be used for teething purposes.

The invention will be better understood by reference to the following description taken in connection with the accompanying 40 drawings in which:—

Figure 1 is a front elevation of a device constructed in accordance with the invention;

Figure 2 is a side elevation of the device; 45 Figure 3 is a vertical or longitudinal sectional view of the device taken on an enlarged scale;

Figure 4 is a transverse sectional view taken substantially on the plane indicated by 50 the line 4—4 of Fig. 3; and

Figure 5 is a plan view of the closure or plug for the open end of the casing, showing this member partly broken away and in

section to show a portion of the reinforcing plate.

Referring more particularly to the drawings, the numeral 1 designates a hollow casing, which is preferably constructed of rubber and is molded so that its external shape is in the form of a two-faced doll. In molding the casing a rib 2 and certain projections are formed upon its exterior and these may be used for teething purposes.

One end of the casing 1 is provided with a restricted opening 3, while the other end of the casing is left open, but formed upon the inside of the casing at the open end is an annular rib 4.

An ordinary glass nursing bottle 5 is disposed within the casing 1 with a portion of its rubber nipple 6 and a portion of its neck 7 extending through the restricted opening 3. By reference to Fig. 3 it will be seen that the neck 7 of the bottle 5 is provided at its extremity with an external rib or bead 8, and that the open end of the nipple 6 is provided with an external bead 9. The nipple 6 of course fits over the bead 8 of the neck of the bottle so that the bead 9 of the nipple will be disposed in spaced relation to the bead 8. When the neck 7 of the bottle 5 carrying the nipple 6 is inserted through the restricted opening 3 of the casing 1, the bottle is pushed until the material of the casing at the edges of the opening 3 snaps past the bead 8 and becomes disposed between that bead and the bead 9 of the nipple 6. In this way a fluid-tight joint between the neck of the bottle and this end of the casing is provided and the nipple 6 is securely maintained upon the neck of the bottle.

In inserting the ordinary nursing bottle 5 into the casing 1 or withdrawing it from the same, that may be done through the open end of the casing opposite the end having the restricted opening 3. After the bottle 5 has been inserted in the casing 1 through the open end, such end is closed by a removable closure in the form of a plug 10. This plug 10 is preferably constructed of molded rubber, having a thin body portion or disk 11 reinforced with an embedded metallic or other suitable stiff plate 11', and being provided at its edge with an annular flange 12. This flange 12 extends above the upper side of the body portion 11

of the plug and has a lower annular portion 13 formed by an annular groove 14 in the outer side of the body portion 11. The outer side of the flange 12 is provided with an annular groove 14 adapted to receive the annular rib 4 formed upon the inside of the casing 1 adjacent its open end. The flange 12 fits snugly within the open end of the casing 1, the rib 2 fitting in the groove 15, and thus a fluid-tight joint between the plug 10 and the open end of the casing is provided. Thus, the continuous rib 4 and the continuous groove 15 act in the capacity of inter-engaging sealing elements, and while these elements are preferably constructed and arranged as shown, it is obvious that other constructions and arrangements are equally applicable.

Preferably the inside of the casing 1 is a little larger than the outside of the nursing bottle 5, so that a space between these two members is provided. This may be filled with a heating or cooling fluid such as hot or cold water to keep the contents of the nursing bottle either warm or cool which ever is desired.

In order to prevent the walls of the casing 1 from being forced tight against the nursing bottle 5, a plurality of projections 16 are formed upon the inside of the casing 1. These projections extend inwardly for engagement with the outside of the bottle. By reference to Figure 4 it will be seen that some of the projections 16 engage the outside of the bottle 5 while others do not, this being due to the fact that the bottle illustrated in the drawings is of the flat type. It of course is understood that any of the well known forms of nursing bottles may be used in connection with the invention.

Especial attention is directed to the construction of the plug 10. As hereinbefore explained the body portion of this plug is more or less stiff, being reinforced by the reinforcement plate 11'. The annular flange 12 is more or less flexible or yieldable to facilitate proper engagement of the flange with the inside of the casing 1 when the plug is inserted in the open end of the casing. Attention is further directed to the fact that due to the embedded plate 11', the closure 11 is stiff in comparison to the wall of the casing 1. Thus, when the jacketed bottle is held in one or both hands, the lower end of the wall may readily be stripped back upon itself, by pulling upon said lower end with one or both thumbs. When this is done to a sufficient extent, the closure 11 has a tendency to snap out of the lower end of the casing, so that removal of such closure is a very simple matter. As soon as this removal is effected and the jacket or casing is released, its inherent resiliency returns it to its normal shape, in readiness to again

hold the closure 11 frictionally in place, when such closure is inserted. Attention is further directed to the fact that the side wall of the jacket or casing projects below the bottom of the bottle, the closure 11 being also spaced below said bottle bottom. Thus, as the rib or bead 8 of the bottle 5 overlies the upper end of the jacket or casing, said bottle is suspended from said upper end of the casing. The casing wall is sufficiently stiff to effect this suspension as shown clearly in Fig. 3, yet its resiliency permits downward yielding of the bottle under the influence of a vertically acting force. Thus, there is no danger of breaking the bottle if it is dropped on its lower end.

Use of a rubber casing around an ordinary glass nursing bottle in the manner above described is very desirable not only to provide a means for maintaining the nipple of the nursing bottle securely upon the neck of the bottle and providing a container for heating or cooling fluid, but also to provide a protector for the glass bottle. The casing is made of rubber so that the glass bottle would not be broken when accidentally dropped or struck upon a hard article. In case it should be crushed or broken by unusually hard wear, the casing will retain the particles of glass, and there will be little likelihood of the baby or person cutting its hands with broken glass.

By placing the rubber casing having the shape of a doll around the ordinary nursing bottle, the whole is given very much the appearance of a doll, so that the article will be attractive and therefore may be used when travelling or before the public without embarrassment.

If desired, the glass bottle may be removed from the casing and a bell or rattle may be placed therein, so that just the casing may be used as a toy. In this connection it will be pointed out that a baby will make use of the rib 2 as a teething ring.

From the foregoing description taken in connection with the accompanying drawings, the construction, use and advantages of the invention will be readily understood, so that further explanation is not considered necessary.

It is obvious that numerous changes in form, proportion, and in various of the details of construction may be resorted to without departing from the spirit and principle of the invention and without sacrificing any of the advantages thereof, so that it is to be understood that these may be made within the meaning and scope of the appended claims.

I claim:

1. A nursing bottle comprising a bottle, the neck of which is provided with an external bead, a nipple fitted upon the neck

- of said bottle over said bead and provided at its end with a bead surrounding the neck of said bottle in spaced relation to the bead of said neck, and a fluid-tight casing surrounding said bottle and having one end provided with a restricted opening through which a portion of said nipple and a portion of the neck of said bottle extends, the material of said casing at the edge of said opening being yieldable and yieldably fitting against the portion of said nipple surrounding the neck of said bottle between said beads, making a fluid-tight joint between said casing and the neck of said bottle and maintaining said nipple upon the neck of said bottle.
2. In a cushion-jacketed bottle, a bottle having a neck formed with an external bead, a casing surrounding said bottle and projecting below the lower end thereof, and a removable closure for the lower end of said casing spaced below the bottle bottom, the upper end of said casing being contracted
- and having an opening through which the upper end of the bottle neck projects snugly, 25 the bead of said neck overlying the casing, the latter having a sufficient degree of stiffness to suspend the bottle above the aforesaid closure but being elastic to permit downward yielding of the bottle under the influence of a vertically acting force.
3. In a cushion-jacketed bottle, an elastic casing wall adapted to surround the bottle and having an open lower end, and a relatively stiff closure fitting within the open 35 lower end of said wall, said wall and closure having inter-engaging sealing elements readily releasable by stripping a portion of said wall back upon itself, the elasticity of said wall permitting such stripping and serving 40 to restore said wall to its normal shape after removal of the closure.

In testimony whereof I have hereunto affixed my signature.

CLARK F. FISK.

- of said bottle over said bead and provided at its end with a bead surrounding the neck of said bottle in spaced relation to the bead of said neck, and a fluid-tight casing surrounding said bottle and having one end provided with a restricted opening through which a portion of said nipple and a portion of the neck of said bottle extends, the material of said casing at the edge of said opening being yieldable and yieldably fitting against the portion of said nipple surrounding the neck of said bottle between said beads, making a fluid-tight joint between said casing and the neck of said bottle and maintaining said nipple upon the neck of said bottle.
2. In a cushion-jacketed bottle, a bottle having a neck formed with an external bead, a casing surrounding said bottle and projecting below the lower end thereof, and a removable closure for the lower end of said casing spaced below the bottle bottom, the upper end of said casing being contracted and having an opening through which the upper end of the bottle neck projects snugly, 25 the bead of said neck overlying the casing, the latter having a sufficient degree of stiffness to suspend the bottle above the aforesaid closure but being elastic to permit downward yielding of the bottle under the influence of a vertically acting force.
3. In a cushion-jacketed bottle, an elastic casing wall adapted to surround the bottle and having an open lower end, and a relatively stiff closure fitting within the open 35 lower end of said wall, said wall and closure having inter-engaging sealing elements readily releasable by stripping a portion of said wall back upon itself, the elasticity of said wall permitting such stripping and serving 40 to restore said wall to its normal shape after removal of the closure.
- In testimony whereof I have hereunto affixed my signature.
